(57) CLAIM

The ornamental design for an hourglass shaped urn, as shown and described.

DESCRIPTION

FIG. 1 is a front perspective view of an hourglass shaped urn, showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof with a bottom view being the mirror image.

The broken lines depicting alphanumeric characters are for the purpose of illustrating the invention and form no part of the claimed design.
